UNITED STATES PATENT OFFICE.

CHARLES M. HIGGINS, OF NEW YORK, N. Y.

DESIGN FOR A SCREW-CAP.

SPECIFICATION forming part of Design No. 30,669, dated May 2, 1899.

Application filed February 17, 1899. Serial No. 705,896. Term of patent 14 years.

To all whom it may concern:

Be it known that I, CHARLES M. HIGGINS, a citizen of the United States, residing at Brooklyn, in the city and State of New York, 5 have invented and produced a new and original Design for Screw-Caps, of which the following is a specification, reference being had to the accompanying drawings.

Figure 1 is an elevation of a screw-cap, 10 showing my new design on a large scale. Fig. 2 is a plan of the same.

As shown in the drawings, the leading feature of my design consists in a screw-cap spiral rib having a series of protuberances 15 formed on the surface of said rib.

My design is intended mainly for screw-

caps for bottles; but it is evident that it is also applicable to tins, jars, &c.

Having described my invention, what I claim as new, and desire to secure by Letters 20 Patent, is—

The design for a screw-cap having a spiral rib and a series of protuberances on said rib, substantially as described and shown.

In testimony whereof I affix my signature, 25 in the presence of two witnesses, this 15th day of February, 1899.

CHAS. M. HIGGINS.

Witnesses:

WILLIAM J. DRIVER,
WALTER E. CLENDANIEL.
